(57) **CLAIM**

The ornamental design for a humidifying air purifier as shown and described.

DESCRIPTION

FIG. 1 is a front perspective view of a humidifying air purifier showing our new design;

FIG. 2 is a front view thereof;

FIG. 3 is a back view thereof;

FIG. 4 is a left side view thereof where the right side view is a mirror image;

FIG. 5 is a top plan view thereof;

FIG. 6 is a bottom plan view thereof; and

FIG. 7 is a partial enlarged view of the area '7' as identified in FIG. 1; and,

FIG. 8 is a front perspective view showing the state where the upper cover of the claimed design has been opened and placed on the upper water tank.

The broken lines depict portions of the humidifying air purifier that form no part of the claimed design. The dot-dot-dashed broken line shown in FIG. 1 indicates cutoff boundaries for the enlarged detailed portion view and forms no part of the claimed design.
